CLAIM

The ornamental design for a laundry knob, as shown and described.

DESCRIPTION

FIG. 1 is a top perspective view of the laundry knob of the present invention;

FIG. 2 is a first side elevation view of the laundry knob of the present invention;

FIG. 3 is a second side elevation view of the laundry knob of the present invention;

FIG. 4 is a third side elevation view of the laundry knob of the present invention;

FIG. 5 is a fourth side elevation view of the laundry knob of the present invention;

FIG. 6 is a top plan view of the laundry knob of the present invention; and,

FIG. 7 is a bottom plan view of the laundry knob of the present invention.

The dashed broken lines shown in the figures are for the purpose of illustrating portions of the laundry knob and form no part of the claimed design. The dot-dashed broken lines define the bounds of the claimed design and form no part thereof.
